DESIGN FOR A COAT

Louis Dornfest, New York, N. Y.

Application December 21, 1939, Serial No. 89,060

Term of patent 3½ years

To all whom it may concern:

Be it known that I, Louis Dornfest, a citizen of the United States of America, residing in the city of New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The scarf is an integral part of the instant coat.

The characteristic feature of my design resides in the combination on the coat disclosed of the specific sleeve element having stitched tucks entirely around the cuff portion thereof in association with a slide fastener in the rear, as shown.

I claim:

The ornamental design for a coat, substantially as shown and described.

LOUIS DORNFEST.
